UNITED STATES PATENT OFFICE.

JACOB HEINRICH LUDWIG BOETTCHER, OF ORANGE, NEW JERSEY, ASSIGNOR TO SERVICES CORPORATION OF NEW JERSEY, OF ORANGE, NEW JERSEY, A CORPORATION OF NEW JERSEY.

MACHINE FOR STACKING BISCUITS AND THE LIKE.

Application filed June 23, 1925. Serial No. 39,054.

This invention relates to a machine for feeding and stacking articles such, for instance, as biscuits.

It has for an object to provide such a machine which includes means whereby each biscuit as fed from the chute falls only a short distance in forming the stack and whereby each biscuit falls the same distance as each other biscuit in forming the stack.

10 Another object consists in providing such a machine that includes a gradually descending support for receiving the biscuits as they are stacked.

Another object consists in providing such 15 a machine which includes successively operating members for receiving the biscuits as they are stacked, each of said members serving as a means for ejecting the formed stack from the other member, during the course 20 of the operation.

Another object consists in providing such a machine that includes means for automatically interrupting the feed of the biscuits during the said ejecting period.

25 Another object consists in providing such a machine in which the members for receiving the biscuits as they are stacked are given movement in open endless angular paths, in performing the functions of receiving and 30 ejecting the biscuits.

A further object consists in providing certain improvements in the form, construction and arrangement of the several parts whereby the above named and other objects 35 may effectively be obtained.

A practical embodiment of the invention is represented in the accompanying drawings in which

Fig. 1 represents a detail top plan view, 40 partly broken away;

Fig. 2 represents a detail end elevation, partly broken away;

Fig. 3 represents a detail section showing 45 the clutch mechanism which is broken away from Fig. 1;

Fig. 4 represents a detail side view, partly broken away, showing the biscuit feeding, stacking and ejecting mechanism, and the actuating means therefor;

50 Fig. 5 represents a detail section, partly broken away, taken in the plane of the line V—V of Fig. 2 looking in the direction of the arrows;

Fig. 6 represents a detail side view, partly

broken away, showing the biscuit feeding, 55 stacking and ejecting mechanism, with parts of the actuating means removed;

Fig. 7 represents a detail side view, partly broken away, with the stacking and ejecting mechanism in a different position from that 60 shown in Fig. 6;

Fig. 8 represents a detail side view, partly broken away, with the stacking and ejecting mechanism shown in still another position;

Fig. 9 represents a detail section, partly 65 broken away, taken in the plane of the line IX—IX of Fig. 2, looking in the direction of the arrows.

The machine includes a framework that has a base 1 of skeleton formation, together 70 with two pairs of uprights marked 2 and 3.

A main drive shaft 4 is journaled in bearings 5—5 fast to a vertical member 6 composing part of the skeleton base 1. The 75 said shaft projects laterally beyond the frame of the machine, and one end finds support in a standard 7. The said end has a pulley 8 fixed thereto in order to receive power from a suitable source, not shown.

The uprights 3 are adapted to support a 80 plurality of chutes 9, which are arranged side by side, nine being shown in the present instance. These chutes are calculated to receive the biscuits 10 from a conveyor belt or other suitable feeding apparatus. 85

It will be observed that the chutes 9 are slanted downwardly, and the biscuits are intended to be fed from them into receiving troughs 11, one trough being arranged in line with, and intended to cooperate with, 90 each chute.

The biscuits are held in their chutes and properly fed therefrom by a series of wheels 12 which are mounted on a shaft 13 that is journaled in bearings 14—14 formed in 95 brackets 15—15 that project upwardly from the uprights 3.

One of said wheels 12 is mounted above each chute 9 and is arranged to project into the chute far enough to engage the biscuits 100 therein, as clearly shown in Fig. 5. These wheels are preferably composed of some yielding material, such as relatively soft rubber, and their peripheries are also preferably serrated so as to provide a circumferential set of yielding fingers calculated to resiliently press upon the biscuits and thereby restrain their movement or feed them, ac- 105

cording to the designed operation of the machine, without injury.

The shaft 13 that carries these feeding wheels is actuated by means of a sprocket 16 carried on the end thereof and connected by means of a chain 17 with another sprocket 18 that is fast to the end of the shaft 4 opposite to that which carries the pulley 8.

The feed of the biscuits is intended to be 10 intermittent so that there may be a pause in the feed during the period of time occupied in ejecting each complete stack, and this intermittency in the feed is accomplished by providing a slip clutch for securing the 15 sprocket 16 in rotatable engagement with the shaft 13. This clutch is well shown in Fig. 3, and it will be seen that the sprocket 16 has a sleeve 19 which carries a plurality of spring actuated shoes 20 intended to frictionally engage the inner circumference of the drum 21 that is fast on the shaft 13.

This clutch will cause the rotation of the sprocket 16 by the chain 17 to normally rotate the shaft 13 and thereby actuate the 20 feed wheels 12, but means is provided for interrupting this operation, which means consists of a brake which has a shoe 22 adapted to engage the outer circumference of the drum 21. This shoe is carried on the 25 upper end of a rod 23 that slides in guides 24-24 on one of the uprights 3. An expansion coil spring 25 is compressed between the lower guide 24 and a shoulder 26 formed on the rod 23 so as to normally urge the rod 30 downwardly and hold the shoe 22 away from the drum 21. The lower end of the rod 23 carries a roller 27 that rides on a cam 28 fixed on the shaft 4. The said cam has two high 35 spots so that, twice during each revolution, the rod 23 is forced upwardly against the power of the spring 25 so as to positively engage the shoe 22 with the drum 21. This prevents the drum from rotating and thus causes the clutch shoes 20 to slip along the 40 inner circumference of the drum 21 so that the continued rotation of the sprocket 16, at this juncture, fails to transmit rotary motion to the shaft 13.

One of the important features of the invention relates to the means for receiving and ejecting the biscuits, which means includes a pair of members adapted to have motion in endless angular paths, each one 45 traversing a course so as to make it, in effect, revolve about the other; each in turn receiving the biscuits as they are stacked; and each in turn ejecting the stacked biscuits from the other.

These members are shown in front view in 50 Fig. 2 and consist of a pair of right angular arms 29, 30. The arm 29 carries a series, in the present instance nine, of heads 31, each head being of such size, shape and location as to cooperate with one of the chutes 9 and one of the receiving troughs 11.

The arm 30 is likewise provided with the same number of similar heads 32 for a similar purpose.

Each of the arms 29, 30, is mounted and actuated in the same manner as the other, so that it will suffice to describe one in detail. Selecting arm 30 for this purpose, it will be observed that its lower end is pivoted at 55 between the ends of a bifurcated rod 34 that is hinged at 35 in the skeleton frame 1. The 60 said rod 34 carries a roller 36 that travels upon the circumference of a cam 37 fixed upon and rotating with the shaft 4. The configuration of the cam 37 is such as to cause the roller 36 to be elevated and depressed, thereby raising and lowering the arm 30 with heads 32.

The movement of the said arm 30 with heads 32 is further controlled. It is normally urged in a forward direction by a 65 retractile coil spring 38 that is fixed to the said arm at 39 and to the upright 2 at 40. A rearward swinging movement is imparted to the arm 30 by means of a lever 41 which is pivoted at 42 in the upper part of the skeleton framework 1. The said lever is bent at its upper end and carries a roller 43 bearing upon the front of the arm 30. The lower end of the lever has a roller 44 that rides in engagement with the edge of a cam 45 that rotates with the shaft 4. The configuration of the cam 45 is such as to intermittently retract the arm 30 and also permit the arm 30 to be moved forwardly by the spring 38, according to the design of the apparatus. 100

The combined effect of the cams, rollers, lever and spring operating upon the arm 30 is such as to cause the heads 32 carried thereby to move both upwardly and downwardly and to the right and left in such manner as to traverse an open, angular endless path. In other words, the said heads move upwardly, then to the left, then downwardly, then to the right, at the end of which last movement the cycle is completed. 110 This cycle is continuously repeated during the operation of the machine.

As previously mentioned, the arm 29 has the same construction, operating mechanism, movement, and function as the arm 30, so that it will not be described nor will its connected parts be identified by different numerals.

In the operation of the machine, the heads 32 are moved into the position shown in dotted lines in Fig. 6. The biscuits 10 are being fed down through the chutes 9 by the wheels 12 and the first biscuits fall upon the tops of the heads 32. During the continued feed of succeeding biscuits, the heads 32 are gradually moving downwardly under the influence of their actuating mechanism above described so that, as each set of succeeding biscuits is fed to the said heads 32, the latter are moved downwardly about the thickness 120 125 130

of a biscuit until, at the time the said heads reach the lowermost point of their downward movement, the stacks of biscuits have been completely formed thereupon. It will be seen that, owing to this arrangement, each biscuit only falls a slight distance in passing from its chute 9 on to its head 32, thereby obviating the danger of breaking the biscuits. The heads 32 are shown in their partly lowered position in Fig. 7, and in their fully lowered position in Fig. 5. Just as the said heads reach their lowest position, the heads 31 on the arm 29 reach their highest position on their upward stroke and move forwardly over the tops of the heads 32, thereby moving the stacks of crackers off the heads 32 and ejecting the same into the troughs 11. As the heads 31 move forward in this operation the heads 32 begin moving backwardly. This condition of affairs is well shown in Fig. 8. The completion of the ejecting movement by the heads 31 brings them into the same position as is shown for the heads 32, in dotted lines, in Fig. 6, and the operation is now repeated, just as before, except that, in this instance the biscuits are stacked upon the heads 31 during their downward movement and, after the stacks have been completed and the heads 31 have reached the limit of their downward movement, the heads 32, which have now reached the limit of their upward movement, advance over the heads 31 and eject the stacks of biscuits as previously described.

The timing of the operation is such that, during the period that either set of heads is ejecting the stack of biscuits from the other set of heads, the brake shoe 22 is clamped against the clutch drum 21, thereby preventing the rotation of the feed wheels 12, and thus causing an interruption in the feed of the biscuits. Immediately the ejection of the stacked biscuits has been accomplished from one set of the heads 31 or 32, the said brake is released and the biscuit feed proceeds.

In order to prevent the biscuits from sliding beyond the heads intended to receive them, as they pass from the chutes 9, I provide a guard 46 which is arranged transversely of the troughs 11.

The feed wheels 12 not only serve to feed the biscuits as above described; they also, by their yielding engagement, restrain the feed of the biscuits when the feeding movement is interrupted by the brake, as mentioned.

It will be understood that various changes may be resorted to in the form, construction and arrangement of the several parts without departing from the spirit and scope of my invention; and hence I do not intend to be limited to the details herein shown and described, except as they may be included in the claims.

What I claim is:

1. A machine of the character described comprising, a plurality of biscuit-carrying elements, means for depositing biscuits in stacked relationship upon such elements, and means for moving each element so as to be loaded in turn with a stack of biscuits and, in turn, to eject the stacked biscuits from a loaded element. 70

2. A machine of the character described comprising, a plurality of biscuit-carrying elements, means for depositing biscuits in stacked relationship upon such elements, and means for moving each said element in an endless path about the other element for 80 the purpose set forth. 75

3. A machine of the character described comprising, a biscuit feed, biscuit-carrying elements, means for moving the elements in sequence in an endless path partly in adjacency to the feed, the movement of the elements being so timed that after one has received a load of biscuits from the feed, the succeeding element, in approaching its receiving position, ejects said load. 85 90

4. A machine of the character described comprising, a plurality of biscuit-carrying elements, means for depositing biscuits in stacked relationship upon such elements, and cam actuated mechanism for moving each 95 element so as to be loaded in turn with a stack of biscuits and, in turn, to eject the stacked biscuits from a loaded element. 95

5. A machine of the character described comprising, a plurality of biscuit-carrying elements, means for depositing biscuits in stacked relationship upon such elements, and cam actuated mechanism for moving each said element in an endless path about the other element for the purpose set forth. 100 105

6. In a machine of the character described, a rotary biscuit feeding device, said device having a yielding serrated periphery. 110

7. A machine of the character described comprising, biscuit feeding means, means 110 for receiving the biscuits to be stacked, means for ejecting the stacked biscuits, means for interrupting the feed during the period of ejection, and a main drive shaft and cams on said shaft for actuating the receiving, ejecting and interrupting means. 115

8. In a machine of the character described, rotary biscuit feeding means, mechanism for actuating said means, and a brake for restraining said mechanism to interrupt the 120 feeding, said brake including a push rod, a shoe at the upper end of said rod, and rod actuating means adjacent its lower end. 120

9. In a machine of the character described, rotary biscuit feeding means, mechanism 125 for actuating said means, a slip clutch in said mechanism, a brake for causing said clutch to slip to interrupt the feed, a main drive shaft, and means on said shaft for operating said mechanism and said brake. 130

10. A machine of the character described comprising, biscuit feeding means, means for receiving the biscuits to be stacked, means for ejecting the stacked biscuits, a rotary shaft provided with mechanism for operating the receiving and ejecting means, a rotary shaft for operating the feeding

means, and a driving connection between said rotary shafts, said driving connection including a slip clutch.

In testimony, that I claim the foregoing as my invention, I have signed my name this 22nd day of June, 1925.

JACOB HEINRICH LUDWIG BOETTCHER.
